UNITED STATES PATENT OFFICE.

RAYMOND L. O'BRIEN, OF SHERIDAN, WYOMING.

COMBINED WINDOW-SHADE AND CURTAIN-POLE HANGER.

1,116,837.

Specification of Letters Patent.

Patented Nov. 10, 1914.

Application filed October 11, 1913. Serial No. 794,683.

To all whom it may concern:

Be it known that I, RAYMOND L. O'BRIEN, citizen of the United States, residing at Sheridan, in the county of Sheridan and State of Wyoming, have invented certain new and useful Improvements in Combined Window-Shade and Curtain-Pole Hangers, of which the following is a specification.

The subject-matter of the present invention is directed to new and useful improvements in hangers or brackets, such as are employed for properly securing curtain poles and shade rollers to the upper portion of a window casing.

As the principal object this invention aims to provide a device of the character set forth consisting essentially in a hanger rod which is equipped with removable bracket plates whereby it may be secured to the window casing and is adapted to slidably and removably receive a pair of curtain pole brackets and a pair of shade roller brackets.

A still further object is to construct the invention as above described in the nature of a unitary device, making all of the bracket and hanger rod attaching plates substantially similar in details of construction, so that all of the elements of the device may be stamped or cut for the most part from a single die, making it necessary to alter the shape of the metal blanks only in minor details, thus facilitating to a large extent the production of the invention at a reasonable cost.

An additional object is to construct the various shade rollers, window curtain and hanger rod brackets in such manner that they may be applied to or removed from the hanger rod with a minimum expenditure of time and labor and to equip the said devices with simple but efficient fastening means, whereby the said devices may be easily clamped in adjusted position on the hanger rod.

The above and additional objects are accomplished by such means as are illustrated in the accompanying drawings, described in the following specification and then more particularly pointed out in the claims which are appended hereto and form a part of this application.

With reference to the drawing, wherein I have illustrated the preferred embodiment of my invention as it is reduced to practice, and throughout the several views

of which similar reference numerals designate corresponding parts, Figure 1 is a fragmentary perspective view of a window casing, of conventional design, showing the improved curtain and shade supporting device in use, the curtain pole and shade roller being shown in dotted lines to permit disclosure of structure which would otherwise be hidden; Fig. 2 is an end view of the device shown in Fig. 1; Fig. 3 is a perspective view of one of the supporting brackets employed in attaching the hanger rod to the window casing; Fig. 4 is an elevation, showing the inner side of the bracket shown in Fig. 3, a part of the bracket housing being shown in section; Fig. 5 is a perspective view of one of the shade roller supporting brackets removed from the hanger rod; Fig. 6 is a perspective view of one of the curtain pole supporting brackets removed from the hanger rod, a portion of said bracket being broken away to show certain features in its construction.

Proceeding now to the description of the drawings, it will be observed upon reference to Fig. 1, particularly, in which the various elements of the invention are illustrated in assembled relation, that the preferred embodiment of this invention includes a hanger rod 10, a pair of terminally disposed attaching brackets or plates 11 and 12, whereby the hanger rod may be secured to the window casing, a pair of shade roller brackets 13 and 14, and a pair of curtain pole brackets 15 and 16. The hanger rod is formed in the nature of an elongated metallic bar which is rectangular in cross section. In this connection it may be well to state that while the preferred form of the hanger rod is formed of light steel or some other metallic substance, wood, or any other suitable composition may be employed when found desirable. The purpose of forming the hanger rod with a rectangular cross sectional conformation is to assist in holding the various attaching brackets and curtain pole and shade roller brackets against rotation upon the hanger rod, as will hereinafter become more apparent.

Coming now to the description of the preferred form of the attaching plates or brackets which are employed, in securing the hanger rod in the desired position, at the upper portion of the window casing, these elements of the invention are similar in construction and it is deemed necessary

therefore to describe only one of them in detail. Reference will now be had, therefore to Fig. 4, in which one of the elements named is illustrated in detail. As will be noted upon reference to this figure, the hanger rod attaching plate or bracket consists in its preferred embodiment of a metallic plate, the body portion of which is designated by the numeral 17. This body portion 17 may be of any desired form although in the preferred embodiment it is fashioned from a metallic blank which is substantially rectangular, but which is cut away diagonally at one portion, as indicated at 18. This construction as above described constitutes, as indicated, the preferred embodiment, but it is, of course obvious, that if so desired, the body portion 17 of the hanger rod attaching bracket may be rectangular, oblong, elliptical, or any other desired shape, inasmuch as this feature is merely a matter of design and constitutes no element of the invention. Apertures 19 are formed adjacent the rear edge of the body plate 17 for the purpose of permitting of the insertion of screws, or other fastening devices, as are ordinarily employed in securing devices of this character to their supporting structure. On the forward portion of the upper edge of the body plate 17 there is formed a housing 20 which in conjunction with the adjacent face of the body-plate 17 forms a U-shaped casing. The bight portion of this casing, which is indicated by the numeral 21 is extended at the forward portion to produce an attaching tongue 22. This tongue 22 is of such length that it may be bent adjacent its junction with the bight portion 21 to form a substantially square tube 23. The free end of the tongue 22 is directed rearwardly through the U-shaped casing above described and is apertured to receive a locking bolt 24 which is insertible through a registering aperture of the bight portion 21 of the U-shaped casing.

From the foregoing and upon reference to Fig. 1 it will be noted that in applying the attaching plate or bracket to the hanger rod, the tube or socket member 23 is slidably mounted on the terminal of the hanger rod and the nut 25 of the locking bolt 24 is applied to the bolt to produce the necessary frictional engagement between the walls of the tube or socket 23 and the squared faces of the hanger rod.

It will be obvious from the foregoing description that by manipulating the nut 25 the hanger rod may be adjusted to any desired position with respect to the bracket, thereby adapting the hanger rod and brackets for attachment to window casings of various widths.

Relative to the formation of the brackets which, as above described, are employed in

securing the hanger rod to the window casing, it is of course to be noted that the U-shaped casings are formed on opposite sides of the two body plates so that the inner faces of the body plates may be disposed against the edges of the window casing. In this connection it may be well to emphasize the fact that the rear end of the U-shaped casing of each bracket assists in mounting the body plate in the desired position on the window casing, inasmuch as it forms a shoulder limiting the rearward movement of the body-plate across the edge of the casing, as will be readily apparent upon reference to Fig. 1.

In order to insure the secure mounting of the bracket plates 11 and 12 on the hanger rod and to assist the tube 23 in holding the hanger rod against rotation, V-shaped notches have been formed in both walls of the outer terminal of the housing 20 as indicated at 26. From observation of Fig. 1, it will be noted that each notch is adapted to receive two sides of the hanger rod and co-act with the opposite sides 27 and 28 of the tube 23 in holding the hanger rod against rotation. The shade roller brackets 13 and 14 are, as regards the formation of the attaching tube or socket, by which they are secured to the hanger rod 10, substantially similar to the bracket plates 11 and 12. One of these shade roller brackets is illustrated in detail in Fig. 5, to which reference will now be had, particularly.

In the preferred embodiment, each shade roller bracket includes a body portion 29, the sides of which are bent at right angles and to extend in parallel spaced relation to each other, producing the side walls 30 and 31. The body portion 29 is extended beyond the terminals of the side plates and is bent to produce a tubular socket similar to the member 23 of the attaching plate or bracket, previously described. The free terminal of the tube thus formed is directed rearwardly through the space defined by the side plates and is terminally apertured to receive a locking bolt 32 which is insertible through a registering aperture formed in the body portion 29. The locking bolt 32 is of course provided with a nut 33 for the obvious purpose of producing the necessary frictional engagement between the walls of the tube and the sides of the hanger bracket 10. V-shaped notches are cut in the terminals of the side plates 30 and 31 at the ends thereof adjacent the tube to receive the hanger rod 10 in the manner previously described in regard to the V-shaped notches of the body plate 17 of the attaching bracket or plate 11. A bayonet slot 34 is cut in the side plate 31 to receive the one terminal lug of the shade roller, the horizontal portion of the bayonet slot being extended to a point approximately midway of the body portion 130

29 to permit the application of the lock in the usual manner. This slot is of such width that it will snugly receive the terminal lug of the shade roller bracket but will hold it 5 against rotation. The bayonet slot above described is provided in only one shade roller bracket, the side walls of the other bracket being formed with a circular aperture adapted to receive the usual rounded 10 lug of the conventional shade roller.

Upon reference to Fig. 1, it will be noted that the body portions of the shade roller brackets are mounted in dependent relation to the hanger rod and support the shade 15 roller in the usual manner. Relative to the peculiar advantages derived from the notches formed in the shade roller bracket, above described, it may be noted, as a matter of primary importance, that the brackets 20 need not be tacked, nailed, or otherwise secured to the window casing, but are slidably mounted on a hanger rod, whereby they may be adjusted to the desired spaced relation to accommodate shade rollers of various 25 lengths.

The curtain pole supporting brackets, previously designated by the numerals 15 and 16, are duplicates of each other and greatly resemble, in construction, the 30 brackets previously described. Each of these brackets includes a U-shaped body or casing 35, the bight portion of which is extended at one end to provide a tongue 36 corresponding to the tongue 23 of the hanger rod supporting bracket and similarly bent to form a resilient squared tube through which the hanger rod 10 is passed. The end portion of this tongue and the bight 35 portion of the casing 35 are provided with aligned apertures to receive a bolt 37 having a nut 38 by means of which the tube may be clamped about the hanger rod to secure the bracket in adjusted position. The side portions of the body of the bracket have those 45 ends adjacent the tongue 36 notched as at 39 to co-act with the tongue 36 in securing the bracket in place, these notches corresponding with those previously described in connection with the brackets 11-12 and 50 13-14.

One of the sides of the U-shaped casing or body member 35 of the bracket is provided with an integral extension 40 which is bent over to partially close the casing, as 55 clearly shown in Fig. 6, and which at its end has a tongue 41 which is rebent inwardly. This extension 40 is perforated to receive a pin or stud 42 having a squared head 43 which seats between the inner face 60 of the extension 40 and the inbent tongue 41 and which holds the stud against turning movement, due to engagement of its angular faces against the side walls of the casing 65 and against the bight portion formed by rebending the tongue 41.

The bight portion of the body of the bracket at that end opposite the tongue 36 is provided with a relatively short tongue 44 which is bent upwardly to close the outer end of the casing and give the same a neat 70 and finished appearance. The free edge of this latter tongue preferably seats beneath the inbent tongue 41 to additionally support the extension 40 and so take up in part the weight of the curtain pole and its curtains, 75 the curtain pole being perforated adjacent its ends to seat over the studs 42 of the brackets as shown in Figs. 1 and 2.

The above described brackets may be constructed in any desired shape and size and 80 from any suitable material. They are preferably formed, however, from sheet metal of suitable weight and of such a nature as to furnish the requisite resiliency to the clamping tongues and tubes.

The brackets and hanger rod may be 85 plated, nickelated japanned or otherwise coated for the purpose of ornamentation, if desired.

Although the hanger rod 10 is illustrated 90 as rectangular in cross section, it will be apparent that the same may be of any desired cross sectional shape, save circular, and be equally effective, the clamping sleeves, of course, in each instance, being shaped in 95 conformance with the cross sectional shape of the hanger rod as also are the co-acting notches. In other words, various changes in the minor details of construction, within the scope of the appended claims, may be 100 made at any time, without in the slightest degree departing from the spirit of the invention.

Having thus described the invention, what 105 is claimed as new is:

1. A combined window shade and curtain 110 pole hanger including a hanger rod, a plurality of supporting brackets movable longitudinally of the rod, clamping means carried by the brackets and engageable about the 115 rod, and means controlling the clamping means.

2. A combined window shade and curtain 120 pole hanger including a hanger rod, a plurality of longitudinally adjustable supporting 125 brackets mounted on the rod, a resilient clamping member carried by each of said brackets and engageable about the rod, and means for contracting the clamping means for causing the clamping means to grip the rod whereby the brackets may be held against movement.

3. A combined window shade and curtain 130 pole hanger including a hanger rod and a plurality of brackets slidable upon the rod 135 and adapted to be clamped in adjusted position thereon, each of said brackets including a casing portion having spaced walls abutting by one end against the hanger rod, and a resilient clamping tongue bent to engage 140

about the hanger rod to co-act with said abutting walls to clamp the bracket in place.

4. A combined window shade and curtain pole hanger including a hanger rod and a plurality of brackets slideable upon the rod and adapted to be clamped in adjusted position thereon, each of said brackets including a casing portion having spaced walls abutting by one end against the hanger rod, and 10 a resilient clamping tongue bent to engage about the hanger rod to co-act with said abutting walls to clamp the bracket in place, said clamping tongue extending by its free end between the spaced side walls, a clamp- 15 ing bolt passed through the free ends of the tongue and the casing portion and a clamping nut upon said bolt.

5. A combined window shade and curtain pole hanger including a hanger rod, a plurality of supporting brackets mounted on the rod and adapted to be adjusted longitudinally thereon, a resilient clamping member carried by each bracket, each clamping member embracing the rod and normally 25 springing away from the bracket whereby the same may be moved freely on the rod, and a fastening device carried by each bracket and engageable with the clamping member thereof whereby the clamping member 30 may be grippingly engaged with the rod for holding the bracket against movement thereon.

6. In a combined window shade and curtain pole hanger, the combination with a hanger rod non-circular in cross section, of 35 brackets movable longitudinally of the rod and adapted to be clamped in adjusted position thereon, each bracket including spaced side walls provided at one end with notches 40 adapted to abut against one side of the hanger rod, resilient tongues extending from the brackets beyond the side walls and bent about the hanger rod to frictionally engage the same, the free ends of said tongues terminating between the side walls, and clamping 45 means co-acting with said tongues to bind the hanger rod between the tongues and the ends of the side walls.

7. A combined window shade and curtain pole hanger including a hanger rod and a plurality of brackets slideable upon the rod and adapted to be clamped in adjusted position thereon, each of said brackets including a casing portion having spaced walls which are terminally notched to receive a portion 55 of the rod, a resilient clamping tongue formed integrally with the casing and having its inner end bent to embrace the hanger rod to co-act with the walls of the casing in clamping the bracket in place, the free end 60 of the tongue extending between the said spaced walls of the casing portion, a clamp- 65 ing bolt passing through the free terminal of the tongue and the connecting wall of the casing, and a clamping nut upon the bolt.

8. A combined window shade and curtain pole hanger including a hanger rod and a plurality of brackets slideable upon the rod and adapted to be clamped in an adjusted position thereon, one of said brackets includ- 70 ing a body member, a housing carried thereby and forming in connection therewith a substantially U-shaped casing, there being substantially V-shaped transversely alined notches formed in the terminals of the body 75 member and one wall of the said housing, a resilient clamping tongue formed integrally with the bight portion of the said U-shaped casing, said tongue being bent intermediate its length to form in connection with the 80 notched terminals of the said body member and wall of the U-shaped housing a square tube for the reception of the hanger rod, the free end of the said tongue being directed inwardly to lie within the limits of the said 85 casing, a clamping bolt passing through the free end of the tongue and through the housing, and a nut threaded upon the bolt for clamping the intermediate portion of the tongue against the hanger rod.

In testimony whereof I affix my signature in presence of two witnesses.

RAYMOND L. O'BRIEN. [L.S.]
